UNITED STATES PATENT OFFICE.

MARCUS M. HUEBSCH, OF CHICAGO, ILLINOIS.

DOOR-CONTROLLING AND SIGNALING SYSTEM.

1,217,180.

Specification of Letters Patent. Patented Feb. 27, 1917.

Application filed June 13, 1914. Serial No. 844,856.

To all whom it may concern:

Be it known that I, MARCUS M. HUEBSCH, a citizen of the United States, residing at 4814 Champlain avenue, Chicago, in the county of Cook and State of Illinois, have invented a certain new and useful Improvement in Door-Controlling and Signaling Systems, of which the following is a full, clear, concise, and exact description, reference being had to the accompanying drawings, forming a part of this specification.

My invention relates to a door controlling and signaling system.

Systems for controlling the unlocking of doors from a remote point have heretofore been known, but these systems have been operated at a great disadvantage, inasmuch as the operator is unable to ascertain the condition and operation of the parts of the system, and unsatisfactory service has resulted.

With the limitation of the prior art in mind, the present invention has been conceived with the object of combining a signaling system with the control system.

Another object of the invention is to provide an improved control cabinet or panel to house the terminal parts of the system.

A further object is to provide a combined call and control system of improved and simplified construction.

Other and incidental objects will become apparent as the description of my invention proceeds.

In the operation of electrically actuated door controlling systems heretofore known the operator has been unable to ascertain, first whether the system be in proper operative condition, second whether manipulation of the control mechanism actually results in opening of the door, and third, whether, after the door were once opened, it be properly closed again.

My invention provides means for informing the operator on the above and other points.

The invention will now be briefly described in connection with the accompanying drawings.

Figure 1 is a front elevation, with parts broken away, of the control panel;

Fig. 2 is a section on the line 2—2 of Fig. 1, looking in the direction of the arrow;

Fig. 3 is a view of one end of the outlet box, the cover plate, thereof, being removed;

Fig. 4 is a rear view of the cover plate 55 with the edges thereof broken away;

Fig. 5 is a view of the door switch;

Fig. 6 is a view of the door unlocking magnet and mechanism;

Fig. 7 is a diagram of the electrical circuits employed.

The control panel 1, shown in Fig. 1, is located at some convenient point in the interior of the building and is connected to the door by means of a speaking tube, the 65 mouth-piece 2 of which terminates on the control panel 1, as shown in Fig. 1. A signal, in this case shown as an electric bell 3, is controlled by a push button at the door to notify the operator that entry through the 70 door is desired. Communication may be had through the speaking tube and the operator may release the locking of the door by depressing the push button 4 located on the control panel.

The control panel 1 comprises a cover plate 5 and a terminal or outlet box 6 which is let into the wall so that the cover plate 5 may be flush with the wall. The outlet box 6 is an open sheet metal box formed by bending up the edges of a sheet metal plate and securing the sides and ends together by means of an angle clip 7 at each end of the box. This angle clip has extending ears 8 which are bent to inclose the end of the box 85 and to be attached to the sides of the same. In this manner the ends and sides of the box are secured together without the formation of any seams in the corners of the box. The depending portion of the angle clip 7 90 is attached to the end wall 9 of the box and the other portion of the clip is flush with the open end of the box and serves to secure the box to the wall into which it is set and to provide also a mounting for the 95 cover plate 5.

An aperture 10 is cut in the bottom of the box to allow the speaking tube 12 to connect with the mouth-piece 2 mounted on the cover plate 5.

A suitable insulated bushing 13, shown in dotted lines in Fig. 3, provides an outlet for the electrical connections to the various parts mounted in the box and on the cover plate. A lamp socket 14 is mounted in the 105 outlet box in such a position that the incandescent bulb 15 will be positioned behind the crystal 16 so that when the lamp

selves to those skilled in the art, all of which I consider to come within the spirit and scope of the present invention.

What I claim as new and desire to secure by Letters Patent of the United States is:

1. In a door unlocking system, a release magnet at the door, a push button at a point remote from said door and a circuit including a source of current, said circuit connected to said push button and said release magnet, a signal in series with said magnet and means controlled by opening of the door for displaying said signal.
2. In a door controlling system, the combination with an audible alarm operable from a remote point, an electromagnetically controlled lock, a source of energy, a circuit closer to release said lock, of a visual signal arranged in series with the lock electromagnet and a shunting circuit closer to short circuit said visual signal when the door is opened to indicate such movement of the door.
3. The combination with a door lock operable by an electromagnet and a circuit in which said magnet is interposed, of a source of electrical energy, a circuit closer, an audible alarm operable from a point remote thereto, a visual signal arranged in series with the electromagnet, a shunt circuit interposed between the source of energy and said electromagnet, a circuit closer interposed in said shunt circuit and operable by the door, whereby when the door is open said shunt circuit will be closed and said visual signal short circuited.

4. In a door lock control, the combination with a door lock, an electromagnet to control the lock, a circuit in which said magnet is interposed, and a source of energy, of a circuit closer to admit current to the electromagnet to unlock the door, a visual signal in series with the electromagnet, an audible alarm receiving current from said source and operable from a remote point, a shunt circuit bridging the visual signal, and a circuit closer interposed in said circuit and operable by the door to short circuit said signal when the door is opened.

5. In a door lock control, the combination with a lock, an electromagnet operatively associated therewith, and a source of electric energy, of a main having a circuit closer therein controlling energization of said electromagnet, a visual signal interposed in series with the electromagnet, a branch conductor having an audible alarm therein, a shunt conductor between the electromagnet and the visual signal and connected to the source of supply to furnish a current return of less resistance than the audible signal, and a circuit closer in said shunt conductor to close the latter when the door is in closed position and thereby short circuit the visual signal.

In witness whereof, I hereunto subscribe my name this 6th day of June, A. D. 1914.

MARCUS M. HUEBSCH.
